UNITED STATES PATENT OFFICE.

GIULIO SILVESTRI, OF VIENNA, AUSTRIA-HUNGARY.

VALVE-COCK FOR ROTARY MOTORS.

SPECIFICATION forming part of Letters Patent No. 609,562, dated August 23, 1898.

Application filed December 30, 1897. Serial No. 664,632. (No model.)

To all whom it may concern:

Be it known that I, GIULIO SILVESTRI, engineer, a subject of the Emperor of Austria-Hungary, residing in the city of Vienna, in the Province of Lower Austria, in the Empire of Austria-Hungary, have invented certain new and useful Improvements in Distributing Valve-Cocks for Rotary Motors, of which the following is a specification.

10 This invention relates to a distributing valve-cock for motors with rotating piston which permits to vary the expansion and, if desired, to reverse the engine, and, further, to stop the admission of the driving medium entirely.

15 My improved valve-cock is characterized by a plug mounted upon the motor-shaft and rotating with the piston of the motor in the same direction and with the same velocity.

20 To this plug steam is constantly conducted and is distributed uniformly from the annular space in the interior of the plug through radial slots. In order to effect variations in the expansion, the plug is surrounded by a 25 mantle composed of two parts which form a free space between themselves by means of variable laps. Accordingly steam is allowed to enter for a longer or shorter period into the motor through the distributing-channels, 30 whereby the variations in the expansions are effected.

My invention is illustrated in the accompanying drawings in different sections and elevations.

35 Figure 1 is a central section. Fig. 2 is a cross-section on line H H of Fig. 1. Fig. 3 is a cross-section of the complete valve-cock on line H H of Fig. 1. Fig. 4 is an elevation; Fig. 5, an axial section; Fig. 6, a plan; Fig. 7, a bottom view. Fig. 8 is a cross-section of the expansion-mantle on line z z of Fig. 4. Fig. 9 illustrates the surface of the mantle in the developed state. Fig. 10 represents the relative location of the slots in the 40 plug and of the recesses in the expansion-mantle at the beginning of admission of steam for the rotation of the motor in the direction of the hand of a watch. Fig. 11 shows the same as Fig. 10 for the reversed rotation of the motor. Figs. 4 to 11 are drawn to a reduced scale as compared to Figs. 1 to 3.

The valve-cock is surrounded by a casing K. The plug k above mentioned is fixed upon the motor-shaft and rotates within the casing simultaneously with the piston and with the same velocity. The plug k is provided with a circumferential groove or channel k', which communicates with an annular space k³ on the shaft g by means of symmetrical openings k² k². The space k³ extends nearly 55 through the whole length of the plug k, so that the pressure medium entering through the short tube e passes through the annular groove k' and openings k² k² into the annular space k³, from where it is distributed 60 through two diametrically opposite slots k⁴ k¹⁴ into the tubes e' e² and from there into the pipes connected with them. By means of the above-described arrangement the plug k, which constantly receives steam, is relieved 65 from overpressure.

70 The plug k is surrounded by an expansion-mantle composed of parts M' M². The shape of these two parts is shown in Figs. 4 to 9.

75 The mantle-pieces consist of an annular portion M' M², having each two laps m' m' m² m². The laps m' m' extend toward the circular mantle portion M², and laps m² m² likewise extend toward the circular portion M'. They are placed diametrically to each other 80 in the cone-shaped mantle. The arc of each lap corresponds in the drawings to a center angle of forty-five degrees, so that by the turning of the mantle portions M' M² toward each other there are formed either two openings 85 each of ninety degrees or four openings of together one hundred and eighty degrees in such a manner that two adjoining openings aggregate ninety degrees. The angles must not be exactly forty-five degrees. They 90 may vary; but two opposite laps of one and the same mantle must have an equal length of the arc and equal center angles.

95 One of the mantle-pieces M' is provided with a slot m³ for the admission of steam. While the machine is in operation one mantle-piece M' or M² is always stationarily secured, the variations in the expansion being effected by turning the other mantle-piece.

100 In Figs. 3 to 10 is illustrated, as an example, the position of the expansion-mantle for the rotation in the direction of the hand of a

watch. Accepted that the mantle-piece M' is stationarily secured while the mantle-piece M^2 , of which only two laps $m^2 m^2$ are shown in Figs. 3 and 10, is adjusted for the desired 5 expansion by any suitable device, the steam enters through the openings $m^3 m^3$ into the annular channel k' . It passes then through the openings $k^2 k^2$ into the annular space k^3 and from there into the diametrically opposite 10 slots $k^4 k'^4$. Accepted plug k occupies the position shown in Fig. 10 and rotates in the direction of the hand of a watch, then steam enters the short pipes $e' e^2$ until the slots $k^4 k'^4$ pass the mantle-openings $m^5 m^5$. In this 15 moment the closing of the steam-inlet commences, and is completed when the slots $k^4 k'^4$ are perfectly covered by the laps $m^2 m^2$. If the plug continues to rotate, then the slots $k^4 k'^4$ will arrive in front of the mantle-openings $m^4 m^4$, which then are filled with steam; 20 but since this steam cannot enter the cylinder it does not interfere with the rotation of the motor. If the rotation is further continued yet, then the slots $k^4 k'^4$ will arrive in a 25 retrograde succession in front of the steam-channels, admitting again steam to the cylinder a .

The slots $k^4 k'^4$, as well as the laps $m' m'$ $m^2 m^2$, being exactly diametrically opposite 30 to each other and having the same surface, it is obvious that the admission of steam is effected simultaneously on both sides and the two dead-spaces $m^4 m^4$ receive steam at the same time and are closed simultaneously, like 35 the steam-channels, relieving thus the plug k in any position.

In case the mantle-piece M^2 is turned in such a manner with reference to M' that the dead-spaces $m^4 m^4$ are diminished then the degree 40 of expansion is increased, because the slots $k^4 k'^4$ will communicate for a longer period with the steam-channels $m^5 m^5$ and steam will pass from the plug k for a longer period into the tubes $e' e^2$. If the mantle-piece M^2 , 45 Fig. 10, is turned so far in the direction of the hand of a watch that its laps $m^2 m^2$ bear against the laps $m' m'$ of the mantle-piece M' , then the highest degree of expansion is attained. The degree of expansion also 50 depends upon the arcs described by the laps. The smaller the arcs of these laps are the

larger is the relative dislocation of the mantle-pieces.

The reversion of the motor is effected in the following manner: The mantle-piece M^2 55 is brought into the position shown in Fig. 11 and is secured there while the mantle-piece M' is loosened and used now for varying the degree of expansion. As soon as the desired degree of expansion is attained then M' also 60 is secured. The mantle-piece M' may further be turned so far that its laps $m' m'$ close the openings for the admission of steam on the opposite side. If this is done, then mantle-piece M^2 may be used for varying the degree 65 of expansion.

The several phases during the reversed rotation of the motor are the same as described while the motor is rotating in the direction of the hand of a watch, and the turning and 70 securing of the mantle-pieces may be effected in any suitable manner by a lever or by a governor.

Having thus described my invention, I claim—

1. A valve-cock for rotary motors consisting of a plug k mounted stationarily upon the piston-shaft and rotating with the same and being provided with radial groove k' and symmetrical openings k^2 , k^2 , an annular space 80 k^3 around the shaft, diametrically opposite slots $k^4 k'^4$ and tubes e', e^2 in combination with an expansion-mantle composed of adjustable circular portions M' , M^2 provided with laps m' , m' , m^3 , m^2 and slot for the admission of 85 the driving medium, and steam-channels substantially as described.

2. In a valve-cock for rotary motors an expansion-mantle composed of adjustable circular portions M' , M^2 provided with laps m' , 90 m' , m^2 , m^2 , placed diametrically to each other in the mantle and extending toward each other, slots for the admission of the driving medium and steam-channels m^5 , m^5 in the mantle, as specified.

In testimony whereof I have signed this specification in presence of two subscribing witnesses.

GIULIO SILVESTRI.
